UNITED STATES PATENT OFFICE.

SAMUEL LESTER ROSS, OF LOCKPORT, NEW YORK, ASSIGNOR OF ONE-THIRD TO FRANK TROZZO AND ONE-THIRD TO JOSEPH ROTONDO, BOTH OF LOCKPORT, NEW YORK.

LIFE-PRESERVER.

1,245,033.

Specification of Letters Patent. Patented Oct. 30, 1917.

Application filed March 16, 1917. Serial No. 155,265.

To all whom it may concern:

Be it known that I, SAMUEL L. ROSS, a citizen of the United States, residing at Lockport, in the county of Niagara and State of New York, have invented certain new and useful Improvements in Life-Preservers, of which the following is a specification.

My invention relates to improvements in life preservers, and it consists in the constructions and arrangements herein described and claimed.

An object of my invention is to provide a life preserver formed into the shape of a garment or coat and being adapted to be inflated with air so that the coat may have the required buoyancy to support a person wearing the coat in the water.

Another object of the invention is to provide a life preserver formed as a coat and including a collar which when inflated with air will support the head of the person wearing the coat.

Other objects and advantages of the invention will appear from the following specification, reference being had to the accompanying drawings forming a part thereof, in which:

Figure 1 is a perspective view showing the life preserver in use,

Fig. 2 is an elevation of the coat, and

Fig. 3 is a detail view showing the air valve on the front of the coat.

In carrying out my invention I provide a body portion of the coat as at 1. Joined with the body portion of the coat as at 2 is a collar indicated generally as at 3. The collar 3 is secured to the body portion 1 in such a manner that the air compartments within the collar 3, which will be herein-after described are in communication with the air compartment of the body portion 1 of the coat.

The material of which the coat 1 is made is preferably rubberized canvas which will render the garment at once waterproof and air tight as well. The body portion 1 is of a double thickness of material which is securely stitched along the marginal edges as at 4 (see Fig. 3). Sleeves 5 are secured to the coat body 1 and are also double in formation so that they too may be inflated

with air. The sleeves 5 are short and are adapted to reach only to the elbow of the wearer as indicated in Fig. 1.

The sleeves 5 and the double body of the coat 1, are inflated through an air valve 6 which may be of any desired construction. The coat is secured about the body of the wearer by suitable clasps 7. By reference to Fig. 2 it will be observed that a region 8 at the back of the coat is closed in by the stitching 9. This region 8 is not adapted to be inflated with air as are the other portions of the coat but is left solid and may be filled with cork should it be so desired.

Attention is now directed to the peculiar formation of the collar 3. It will be seen that the collar 3 is formed into three peaks or triangular portions 10, 11, 12. The collar 3 is also double in formation similarly as is the body 1 of the coat so that it too may be inflated with air.

As previously stated the connection of the collar 3 with the body 1 of the coat at 2, is such that when the body of the coat is inflated, the collar will also be inflated.

Arranged centrally of the center peak 11 is a triangular or other shaped portion 13 which is isolated from the surrounding portions of the collar by suitable stitching. It will at once be apparent that the stitching with which the double portions of the collar are held together of the triangular portion 13 will form a channel in the central peak 11 which will become inflated with air and leave the central portion 13 depressed. The depressed portion 13 now becomes a rest for the back of the wearer's head as indicated in Fig. 1.

The inflated side members 10 and 12 of the collar 3 will support the wearer's head from the sides also as shown in Fig. 1, and prevent the head from rolling over sidewise should the wearer faint, and thus cause him to drown.

The construction of the device having been described the manner of application is as follows:

The coat 1 is inflated through the medium of the valve 6 and laid aside for use in an emergency. Should it become necessary to don the coat, the coat is fastened about the body by the fastener 7. On entering the

water the peaks 10, 11, 12 of the collar 3 will naturally adjust themselves in an upstanding position as shown in Fig. 1.

It frequently happens that through fright or other causes the wearer of the life preserving coat will faint on entering the water. Were it not for the provision of the side peaks 10 and 12, the head of the wearer might roll over into the water whereupon the wearer would become drowned. By providing the upstanding side portions 10 and 12, accidental drowning of the person is prevented and thus one of the most efficient features of the coat manifests itself.

While the construction and arrangement of the device is generally that of the preferred form, obviously modifications therein may be made without departing from the spirit of the invention or the scope of the claims.

I claim:

1. A life preserver including a coat body having sleeves, a collar having head supporting means attached to the coat, and means for inflating the coat, sleeves and collar.

2. A life preserver including a coat body having sleeves, an inflating valve on the coat, a collar attached to the coat having an inflatable head supporting peak, and a central depressed portion for receiving the wearer's head.

3. A life preserver including an inflatable coat body and sleeves, and an isolated portion at the back of the coat, a clasp for the coat, an inflatable collar attached to the coat having side peaks in air communication with the coat body for supporting

the sides of the wearer's head, and a central inflatable portion on the collar having a central depression for receiving the back of the wearer's head.

4. A life preserver including an inflatable coat body, and an inflatable collar attached thereto for supporting the wearer's head, and inflatable side members for preventing the wearer's head from rolling sidewise when supported by said collar.

5. A life preserver including an inflatable coat body having sleeves, and an inflatable collar attached thereto adapted to support a wearer's head and having a recess or depression for receiving the head.

6. A life preserver including a collar, means for securing said collar upon the shoulders of the wearer, said collar having an inflatable head supporting peak and a central depressed portion for receiving the wearer's head.

7. A life preserver including a collar, means for securing said collar upon the shoulders of the wearer said collar comprising a pair of buoyant side peaks and a central buoyant peak, said central peak having a depression, whereby said peaks will fit upon the wearer's head while said depression will receive the back of the wearer's head, whereby the wearer's head will be supported.

In testimony whereof I affix my signature in presence of two witnesses.

SAMUEL LESTER ROSS.
